UNITED STATES PATENT OFFICE

126,040

DESIGN FOR A MUTE, FOR STRINGED MUSICAL INSTRUMENTS OR THE LIKE

Bernardo Alemany, New York, N. Y.

Application July 1, 1940, Serial No. 92,378

Term of patent 7 years

To all whom it may concern:

Be it known that I, Bernardo Alemany, a citizen of Argentina, residing at New York city, New York, have invented a new, original, and ornamental Design for a Mute, for Stringed Musical Instruments or the like, of which the following is a specification, reference being had to the accompanying drawing, forming part thereof.

In the drawing:

Fig. 1 is a front elevational view of a mute, for stringed musical instruments or the like, showing my new design;

Fig. 2 is a side elevational view;

Fig. 3 is a top plan view; and

Fig. 4 is a rear elevational view thereof.

The dominant features of my design reside in the portions shown in solid black lines in the drawing.

I claim:

The ornamental design for a mute, for stringed musical instruments or the like, substantially as shown and described.

BERNARDO ALEMANY.
